UNITED STATES PATENT OFFICE.

JOHN L. RUPP, OF WILKINSBURG, PENNSYLVANIA, ASSIGNOR TO WESTINGHOUSE UNION BATTERY COMPANY, OF SWISSVALE, PENNSYLVANIA, A CORPORATION OF PENNSYLVANIA.

DESIGN FOR A CASING FOR COMBINED BATTERY AND BATTERY CHARGER FOR RADIO APPARATUS.

Application filed October 30, 1926. Serial No. 19,541. Term of patent 14 years.

To all whom it may concern:

Be it known that I, JOHN L. RUPP, a citizen of the United States, residing at Wilkinsburg, in the county of Allegheny and State of Pennsylvania, have invented a new, original, and ornamental Design for Casing for Combined Battery and Battery Charger for Radio Apparatus, of which the following is a specification, reference being had to the accompanying drawings.

In said drawings,

Fig. 1 is a perspective view of a power unit casing, showing my new design.

Fig. 2 is a side view of said casing.

Fig. 3 is an end view of the casing, and Fig. 4 is a top view of the casing.

I claim:

The ornamental design for a casing for combined battery and battery charger for radio apparatus, as shown.

JOHN L. RUPP.
